UNITED STATES PATENT OFFICE

167,124

SOFA OR SIMILAR ARTICLE

Paul Tuttle, Los Angeles, Calif., assignor to Modern Color, Inc., Los Angeles, Calif., a corporation of California

Application March 24, 1952, Serial No. 19,023

Term of patent 14 years

(Cl. D15—11)

To all whom it may concern:

Be it known that I, Paul Tuttle, a citizen of the United States and a resident of the city of Los Angeles, in the county of Los Angeles and State of California, have invented a new, original, and ornamental Design for a Sofa or Similar Article, of which the following is a specification, reference being had to the accompanying drawing, forming part thereof, in which:

Fig. 1 is a perspective view of a sofa or similar article showing my new design.

Fig. 2 is an end view; and

Fig. 3 is a rear view.

I claim:

The ornamental design for a sofa or similar article, as shown.

PAUL TUTTLE.
